SUPERVISORY-CONTROL SYSTEM

Application filed May 28, 1923. Serial No. 641,900.

My invention relates, in general, to apparatus for controlling and supervising electrical equipment or apparatus from a remote point.

5 More particularly, my invention provides improved means for supervising and controlling the electrical equipment in a number of substations of an electrical distribution system from a central point.

10 One object of my invention is to provide a circuit arrangement for a system of the above-indicated character that requires the operation of the apparatus unit in the distant substation. That is, the operation of initiating the actuation of an apparatus unit at the substation will occur repeatedly, by my invention, until the unit is actuated.

20 Another object of my invention is to provide means for automatically releasing the relay which causes the repeated initiating operation, upon the actuation of the desired apparatus unit.

25 There are other objects of my invention, which together with the foregoing, will be described hereinafter with reference to the accompanying drawing, the single figure of which is a diagrammatic view of a supervising and controlling system.

30 In carrying out my invention, I employ, in general, the scheme used in a well-known printing telegraph system. To explain more fully, there is provided a four-conductor trunk line extending from a central control office to each substation of the system having 35 apparatus units to be controlled and supervised. Associated with each end of the trunk line is a "sunflower" or commutator having a plurality of segments thereon. Motors are provided at each end of the trunk line and are arranged to rotate brushes over the commutator at the central office and at the substation in synchronism. The specific means by 40 which the brushes are maintained in synchronism are the subject of claims in my copending divisional application, Serial No. 293,563, filed July 18, 1928. The circuit connections are so arranged that, when any apparatus unit at the substation changes its condition, a certain battery potential is placed upon a 45 certain segment of the commutator in that

substation. When the rotating brushes engage this segment, a particular signal is operated at the central office to notify a dispatcher of the occurrence at the substation. This signal is, of course, selected by the conjoint action of the brushes over the commutators at each end of the trunk line. 55

To initiate the operation of an apparatus unit, the dispatcher operates a key, which energizes a relay. The relay operates to place a battery potential upon a segment of the commutator at the central office and locks itself energized. In a well known manner, by the conjoint action of the brushes and the commutators at each end of the trunk line, the proper apparatus unit is selected and its operation initiated. The operation of the unit returns a signal to the dispatcher in the usual manner. Upon the return of the signal, the locking circuit of the above-mentioned relay is opened and the battery potential removed from the commutator segment at the dispatcher's or central office. If the apparatus unit is not operated, the relay remains energized and the initiating operation reoccurs until the unit is operated and the proper signal returned to the dispatcher. 70 75

While, in the drawing, I have shown a plurality of batteries at the dispatcher's office and at the substation, it will be understood that it is only necessary to provide two batteries of opposite and equal polarity at the dispatcher's office and at each substation in the system. 80

While I have shown my invention applied to an electrical system of distribution employing automatic substations, it will be understood that this has been done for the purpose of convenience and that it is, by no means, limited to this use. 85 90

Referring now to the drawing, the apparatus on the left of the dotted lines shows the apparatus in the dispatcher's office while the equipment on the right of the dotted lines is that located in the substation. The motor 36 is used for rotating the brushes 50 to 52, inclusive, over the commutator or distributor. The speed of this motor is governed by a centrifugal governor 34. The key K is of the double-throw type and is one of a group of 95 100

keys provided for controlling the apparatus units in the substation. The lamps 32 and 33 are associated with the key K and serve to indicate the condition of an apparatus unit 5 at the substation. The lamps 30 and 31 are monitor lamps to indicate certain conditions to the dispatcher, as will appear hereinafter. Relays 10 and 11 are provided for the purpose of controlling the lamps 30 and 31 and also 10 for controlling certain circuits as will appear. A polarized relay 12 is adapted to control the operation of the supervisory lamps 32 and 33.

The dispatcher's office is connected to the substation by means of a four-conductor 15 trunk line comprising conductors 150 to 153, inclusive.

In the substation, a motor 85 is provided. This motor is similar to the motor 36 in the dispatcher's office already described. The 20 speed of the motor 85 is controlled by a centrifugal governor 86. The motor is adapted to rotate the shaft 83, carrying the brushes 80 to 82, inclusive, over the associated commutators. Relays 90 and 91 are provided for 25 the purpose of controlling a circuit breaker C. A polarized relay 92 controls the circuits of the relays 90 and 91. A time-element or dashpot relay 200 is adapted to attract its armature quickly and to release it slowly in a well 30 known manner.

Only a portion of the equipment in the dispatcher's office and substation has been shown to illustrate the operation of one apparatus unit at the substation. The manner in which 35 a plurality of apparatus units are supervised and controlled will be apparent from this.

Having briefly described the apparatus shown in the drawing, I will now describe its 40 detailed operation.

The motors 36 and 85 are direct-current motors supplied from suitable sources of direct current 38 and 87, respectively. In order to provide still greater accuracy in the synchronous running of the motors, each is fitted with a centrifugal governor 34 or 86 for regulating the current flowing in the field windings.

In accordance with the speed of the motors, 50 the governor is actuated by centrifugal force and more or less resistance is placed in series with the field and armature windings of the motors. By this means, the speed is maintained constant, and synchronous rotation of 55 the shafts 53 and 83 is thus obtained. The motor 36 is adapted to rotate the brushes 50 to 52, inclusive, through the medium of a cone clutch 60' in a clockwise direction. In a like manner, the motor 85 is adapted to rotate 60 the brushes 80 to 82, inclusive, at the substation, in a clockwise direction through the medium of a cone clutch 88 in order to insure that these brushes rotate at substantially the same speed. While I have illustrated my invention as embodying a cone clutch, it will be

understood that any form of clutch may be used.

Polarized relays 60 and 160 at the dispatcher's office and substation, respectively, are provided for securing still more accurate 70 synchronous operation of the brushes 50 to 52, inclusive, at the dispatcher's office and the brushes 80 to 82, inclusive, at the substation. The armatures 61 and 161 of these relays are provided with toggle springs in order to 75 maintain the armatures mechanically in the position last operated. In addition to this apparatus, release magnets 64 and 40 are provided for regulating and adjusting the movement of the brushes 50 to 52, inclusive. The 80 circuits of these magnets are controlled by the polarized relay 60. Likewise, at the substation, the release magnets 164 and 94 control the adjustment of the brushes 80 to 82, inclusive. The circuits of these magnets are 85 controlled by the polarized relay 160 at the substation. The functioning of these relays and magnets maintains the brushes in perfect synchronism, as will hereinafter appear.

In order to describe the synchronizing 90 operation, it will be assumed that the brushes at both the dispatcher's office and the substation are rotating synchronously in a clockwise direction. Thus, when the brush 52 engages the contact 73, the brush 82 at the substation will be in engagement with the contact 183 and a circuit is completed extending from the negative pole of the battery 107 by way of the contact 73, the brush 52, through the winding of the polarized relay 60, the trunk conductor 152, through the winding of the polarized relay 160, the brush 82, contact 183, the positive pole of the battery 190, through the battery, and the trunk conductor 153 to the positive pole of the battery 107. The batteries 107 and 190 are connected in 100 series and the armatures 61 and 161 of the polarized relays 60 and 160, respectively, are forced into engagement with the contacts 63 and 163. The operation of the armature 61 closes a circuit for the release magnet 40 over a path extending from the negative pole of the battery 67 by way of the armature 61, the contact member 63, through the windings 110 of the release magnet 40, and thence to the positive pole of the battery 67. The release magnet 40 is energized over this circuit and attracts its armature 41, thereby withdrawing the latch 42 from the path of the stop 43.

There are five stops such as 43 around the circumference of a disc 75 which rotates on the same shaft as the brushes 50 to 52, inclusive. The armatures of the release magnets 40 and 64 are so arranged with respect to the stops on the circumference of the disc 120 that, in the position shown, the rotation of the shaft 53 will be arrested by the latch 42 controlled by the armature 41 of the release magnet 40, unless it is withdrawn by operation of the magnet at the time that the wiper 125 130

52 engages the contact 73. In case the latch is withdrawn, the shaft will move a portion of another revolution, whereupon its rotation will be arrested by the latch 66, controlled by the armature 65 of the release magnet 64, engaging the stop 76. In this case, the wiper 52 will then be in engagement with the contact 71. In order that the shaft may continue its rotation, the release magnet 64 must 10 then be energized.

15 While the circuit of the relays 60 and 160 is only momentarily completed, the toggle springs cause the armatures to remain in operated position, even though the circuit thereof is opened.

20 As has been described above, the release magnet 40 is energized and the shaft 53 carrying the brushes 50 to 52, inclusive, is allowed to move on.

25 The operation of the polarized relay 160, at the substation, closes a circuit which extends from the negative pole of the battery 180 by way of the armature 161, the contact 163, through the windings of the release magnet 94, to the positive pole of the battery 180. The release magnet 94 is energized over this circuit and operates to attract its armature 95, thereby withdrawing the latch 152 from the path of the stop 166. This operation allows the shaft 83, carrying the brushes 80 to 30 82, inclusive, to rotate farther.

35 It will be understood that the stops such as 166 are arranged on a disc 196 attached to the shaft 83 in the same manner as the stops such as 43 are arranged on the disc 75. The release magnets 94 and 164 have the same functions as the release magnets at the dispatcher's office.

40 If the brushes 50 to 52, inclusive, at the dispatcher's office are in synchronism with the brushes 80 to 82, inclusive, at the substation when engagement is made with the contacts 71 and 181, respectively, a circuit is closed extending from the positive pole of the battery 108 by way of the contact 71, the brush 52, through the windings of the polarized relays 60 and 160, the brush 82 which is now in engagement with the contact 181, the said contact, the negative pole of the battery 191 45 through the battery, the trunk conductor 153 to the negative pole of the battery 108. The polarized relays 60 and 160 are energized over this circuit, but, as the current flows in a direction different from that in the previous case, the armatures 61 and 161 are operated in engagement with the contacts 62 and 162, respectively.

45 The operation of the armature 61 of the polarized relay 60 into engagement with the contact 62 closes a circuit extending from the negative pole of the battery 67, the armature 61, the contact 62, through the winding of the release magnet 64 to the positive pole of the battery 67. The release magnet 64 is energized over this circuit and operates its

5 armature 65, thereby withdrawing the latch 66 from the path of the stop 76 whereby the rotation of the shaft 53 is allowed to continue.

10 At the substation, the operation of the armature 161 of the polarized relay 160 closes a circuit from the negative pole of the battery 180 by way of the armature 161, the contact 162, through the winding of the release magnet 164, and thence to the positive pole of the battery 180. The release magnet 164 is energized over this circuit and operates its armature 95 to withdraw the latch 196 in the path of the stop 197. The shaft 83 is thus allowed to continue rotating.

15 If the brushes remain in synchronism, the release magnets 40 and 94 are operated when the brushes 52 and 82, respectively, engage the bank contacts 77 and 198. This alternate operation of the release magnets 40 and 94 20 and 64 and 164 occurs to withdraw the stops so as to allow the shafts 53 and 83 to rotate.

25 Should the brush 52 lag behind the brush 82 between the contacts 71 and 77, the rotation of the shaft 83 carrying the brushes 80 to 82, inclusive, will be stopped with the brush 82 in engagement with the contact 198 until the brush 52 engages the contact 77 at the dispatcher's office, the clutch 88 being constructed to allow the shaft to be stopped by 30 the latch. The release magnets are then energized and the shafts 53 and 83 are allowed to rotate. As the circuits of the polarized relays 60 and 160 are completed ten times during each revolution of the shaft 53 or 83, the brushes 50 to 52, inclusive, and 80 to 82, inclusive, at the dispatcher's office and the substation, respectively, are thus synchronized ten times each revolution. The synchronizing operation is the same in the 35 event that the brush 82 lags behind the brush 52.

40 Should it ever occur that the brushes 80 to 82, inclusive, lag behind the brushes 50 to 52, inclusive, during the travel of one-tenth of a revolution, the brush 82 may be in engagement with the contact 181 and the brush 52 in engagement with the contact 77. Under these conditions, it is necessary to hold the brush 52 in engagement with the contact 77 45 until the brushes at the substation obtain a corresponding relative position. Assuming that the brushes are in the relative positions mentioned, a circuit is closed extending from the negative pole of the battery 107 at the dispatcher's office, the contact 77, the brush 52, through the winding of the polarized relay 60, the trunk conductor 152, through the winding of the polarized relay 160, the brush 82, the contact 181, the negative pole of the battery 191, through the battery, the conductor 153, to the positive pole of the battery 107. These two batteries are of equal potential and act in the opposite directions. Consequently, the polarized relays 60 and 160 maintain their 50

armatures in the same position, that is, the release magnet 40 at the dispatcher's office and the release magnet 94 at the substation remain energized.

5 The operation of the release magnet 40 at the dispatcher's office has no effect because the latch 43 is not restraining the shaft 53 at this time, the latch that is restraining the movement of the shaft 53 being controlled by the release magnet 64. However, at the substation, the release magnet 94 remains energized to keep the latch 152 from the path of the stop, the shaft 83 being in such position that the latch 152 would restrain its movement. 10 15 When the brush 82 at the substation engages the contact 198, the release magnets 64 and 164 are energized and the brushes are thus brought into synchronism.

20 By the above arrangements, the brushes 50 to 52, inclusive, and the brushes 80 to 82, inclusive, are caused to rotate in absolute synchronism.

25 In order to describe the signalling operation, it will be assumed that the circuit breaker C at the substation opens under automatic control, thus stopping the rotary converter R. The automatic control of the circuit interrupter C is accomplished by means of the overvoltage relay 210 and the undervoltage relay 211. It will be seen that these relays are connected across the power line. The operation is such that, when the voltage of the power line increases to a predetermined value, the relay 210 operates to bring the 30 armature 214 into connection with its working contact, thereby completing a circuit for the tripping coil of the circuit interrupter C. When the voltage of the power line falls to a lower predetermined value, the undervoltage 35 relay 211 is deenergized to permit the armature 215 to engage its resting contact. By the operation of this armature, a circuit is closed for the closing coil of the circuit interrupter C.

40 45 The circuit over which the interrupter C is tripped by the operation of the relay 210 extends from the positive pole of the battery 180, by way of back contact and armature 216, armature 214 and its front contact, trip coil 218 and the auxiliary switch 220 of the circuit interrupter, to the negative pole of the battery 180. The circuit over which the interrupter C is closed extends from the positive pole of battery 180, by way of back contact 50 55 and armature 216, armature 215 and its back contact, closing coil 100, auxiliary switch 219, and thence to the negative pole of the battery 180.

60 In the present case, it has been assumed that the voltage of the line increases to such value that the relay 210 operates the armature 214, thereby completing a circuit for the tripping coil 218 of the circuit interrupter C. When the circuit breaker opens or trips, a circuit is 65 closed extending from the negative pole of

the battery 110 by way of the contact 103, the spring 102, to the segment 84 of the distributor. In this manner, a negative battery potential is placed upon the segment 84. When this segment is traversed by the brush 70 75 80 85 90 95 100 105 110 115 120 125 130 135 140 145 150 155 160 165 170 175 180 185 190 195 200 205 210 215 220 225 230 235 240 245 250 255 260 265 which is now in engagement with the segment 199, the said segment, through the winding of the dash-pot relay 200, through the winding of the polarized relay 92, the trunk conductor 153 to the positive pole of the battery 106. The dash-pot relay 200 immediately energizes and the polarized relay 92 operates its armature 93 in such a direction as to force the springs 96 and 98 into engagement. By 10 the latter operation, a circuit is closed extending from the negative pole of the battery 180 by way of the springs 204, 202 and 205 of the dash-pot relay, the springs 96 and 98 of the polarized relay through the winding 15 of the relay 91, and thence to the positive pole of the battery 180.

The relay 91 is energized over this circuit and operates to close a circuit extending from the negative pole of the battery 180, the 20 springs 204, 202 and 205, the springs 96 and 98, the armature 116 and its front contact, through the winding of the closing coil 100, and thence to the positive pole of the battery 180. The circuit breaker C is operated over 25 this circuit and, in addition, upon the completion of its operation, opens its own circuit in a well known manner. As the circuit of the dash-pot relay 200 is opened at the brush 80, after a short interval, the relay 200 is 30 deenergized to open the circuit of the relay 91, which is also deenergized. It will be understood that the polarized relay 92 controls such other circuits as may be necessary to secure proper starting of the rotary converter 35 R. These have not been shown as they do not concern my invention and are well known.

By the change in condition of the circuit breaker C, a positive battery potential is placed upon the segment 84 of the distributor 40 at the substation and, upon further revolution of its distributor, the polarized relay 12 at the dispatcher's office is operated to place its armature 24 in the reverse position. By the opening of the springs 25 and 26, the locking circuit of the relay 11 is opened and this relay is deenergized.

The retraction of the armatures of the relay 11 removes the negative battery potential from the segment 55, thus stopping the sending operation, at the armature 23 and, at the armature 20, the circuit for the monitor lamp 30 is opened whereby the dispatcher is apprised that the sending operation is completed. During the time that the monitor lamp 30 is lit, the dispatcher knows that the sending operation is being completed so as to initiate the operation of the desired apparatus unit at the station. When the lamp 30 is extinguished, the dispatcher knows that 55 the circuits which control the application of a potential from the battery 106 to the segment 55 have been opened. The operation of the lamp 33 follows as a result of the movement of the armature 24 of the polarized relay 12 as does the effacement of the lamp 32.

By this change in supervisory signals, the dispatcher knows that the desired operation has occurred.

The monitor lamp 31 functions in identically the same manner as the lamp 30 when the key K is operated in the opposite direction 70 so as to cause the engagement of the spring shown on the left to apprise the dispatcher of the application of a battery potential to the segment 55. The lamp 31 is, of course, extinguished after the circuit interrupter at the station is operated and an answer-back signal has been obtained indicative of its operation. The effacement of the lamp 31 then apprises 75 the dispatcher that the sending circuit has been opened.

The provision of the relay 11 takes a great deal of burden from the dispatcher, since it is only necessary for him to momentarily press the control key, such as K, and the sending operation occurs until the proper apparatus unit is operated. In the event that the sending circuit is not completed for some reason, the apparatus will attempt to close the circuit repeatedly until the proper apparatus unit is operated. In a like manner, if the return signal circuit is not completed, the apparatus will attempt to close the circuit successively until the proper answer-back 90 signal is obtained. By these provisions, false 95 operation of the apparatus is guarded against.

The operations which occur when the dispatcher controls similar apparatus units at the substation occur in the same manner as 100 above described.

It will be noted that the circuit of the relay 90 or 91 is only momentarily closed upon the operation of the polarized relay 92. Consequently, the circuit breaker C may be controlled by the relays 210 and 211 in a manner 105 previously described.

Should it be desirable for the dispatcher to be able to lock the device or apparatus unit such as the circuit breaker C from automatic control, all that is necessary is to provide a separate polarized relay at the substation and connect it in the same manner as the relay 92. To control this relay the dispatcher will be provided with a key. This 110 polarized relay, upon operating, will, when operated by the current flow through its windings in a particular direction, complete a circuit over the conductor 221 for the relay 212. The relay 212 is energized to complete 115 a locking circuit for itself at armature 223 and to open the battery connection to the armatures 214 and 215 on the relays 210 and 211, respectively, so that these relays will not 120 function to cause the operation of the circuit interrupter. When the dispatcher desires to return the circuit interrupter C to automatic control, he will operate the proper key so as to cause one of the polarized relays at the 125 station to be operated to complete a circuit 130

over conductor 222 for the relay 213. The relay 213 is energized to operate armature 217 to open the locking circuit of the relay 212. The relay 212 is thereupon deenergized to connect one terminal of the battery to the armatures 214 and 215 at armature 216 in an obvious manner.

The number of apparatus units at the substation that can be controlled and supervised 10 is only limited by the number of segments that can be placed upon the distributors at the dispatcher's office and the substation.

The term "sunflowers" as used herein is intended to define two synchronously moving 15 devices employing commutators, step-by-step switches, relays, or, in fact, any synchronous selecting movement.

Various modifications may be made in the apparatus illustrated without departing 20 from the spirit and scope of my invention, as set forth in the appended claims.

I claim as my invention:

1. In combination, a first station, a second station, a circuit connecting said stations, a plurality of switching means at said first station, manual means for closing said switching means, means for thereafter retaining the switching means in closed position, a plurality of devices at said second station, one for 25 each of said switching means, each movable to a plurality of positions, an electromagnetic means for each device to move it to one of its positions, a second electromagnetic means for each device to move it to the other 30 of its positions, a rotating distributor at each station associated with said circuit, having an individual selecting position for each of said switching means and corresponding devices, means for operating said distributors 35 in synchronism whereby each of said switching means is associated with said circuit successively and simultaneously with its associated device, means including said switching means and the distributor at the first station 40 for transmitting operating currents over the circuit when the distributor reaches a selected position, means including the distributor at the second station responsive to said currents for causing the energization of 45 said first or second electromagnetic means, means whereby said energizing means becomes non-operative to cause the energization of the first or second electromagnetic means upon the cessation of transmission of 50 the current, means controlled by the movement of the device to the controlled position for transmitting an impulse to the first station and means responsive to said impulse for causing the retaining means to cause restoration 55 of the switching means to its original position whereby the operating currents cease.

2. In combination, a first station, a second station, a circuit connecting said stations, a 60 plurality of manually operated switching

means at said first station, means for retaining the switching means in closed position after operation, a plurality of devices at said second station one for each of said switching means, each movable to a plurality of positions, electromagnetic means for each device for operating it to its positions, a rotating distributor at each station associated with said circuit, having an individual selecting position for each of said switching means and corresponding devices, means for operating said distributors in synchronism whereby each of said switching means is associated with said circuit successively and simultaneously with its associated device, means including said switching means and the distributor at the first station for transmitting operating currents over the circuit, means including the distributor at the second station responsive to the currents for 85 causing the energization of said electromagnetic means, means whereby upon the cessation of transmission of the current, said means becomes non-operative to cause the energization of said electromagnetic means, means controlled by the movement of the device to the controlled position and including the distributor, for transmitting an impulse to the first station and means responsive to 90 said impulse for causing the operation of said retaining means to cause the restoration of the switching means to its original position whereby the operating currents cease.

3. In a supervisory control system, a first station, a second station, a plurality of devices at said second station, each of said devices having an open and a closed position, electromagnetic operating means individual to each of said devices, a mechanical connection comprising a part of each of said devices controlled by said electromagnetic operating means for moving said devices to their open or closed positions, each of said operating electromagnetic means having a plurality of parallel circuits, a first electromagnetic controlling means for controlling one of said circuits, a second electromagnetic controlling means for controlling the other of said circuits, a distributor at each of said stations, means for operating said distributors in synchronism, said first electromagnetic controlling means being connected to individual segments on said second-station distributor, means controlled from said first station and including said distributors for transmitting current impulses selectively through said first electromagnetic controlling means for operating said operating electromagnetic means, means responsive to the operation of said first electromagnetic controlling means for closing one of said circuits to the electromagnetic operating means of its associated device, whereby said device is operated to its closed position, means responsive to the operation of said device from 125 130

its open to its closed position for stopping
the transmission of current impulses through
said first electromagnetic means, means
whereby upon the cessation of the impulses,
5 said first electromagnetic means is rendered
non-operative to close said first circuit of
the electromagnetic operating means and a
circuit controlled by said device when in
closed position, said second controlling elec-
10 tromagnetic means being responsive to the
conditions of said circuit for closing said
second circuit of the electromagnetic means
associated with its device.

In testimony whereof, I have hereunto sub-
15 scribed my name this 26th day of May, 1923.

ROY J. WENSLEY.
